UNITED STATES PATENT OFFICE.

WILLIAM H. NEHLS, OF PORTAGE, WISCONSIN.

FURNACE.

1,362,259.

Specification of Letters Patent.

Patented Dec. 14, 1920.

Application filed March 19, 1919. Serial No. 283,532.

To all whom it may concern:

Be it known that I, WILLIAM H. NEHLS, a citizen of the United States, residing at Portage, in the county of Columbia and State of Wisconsin, have invented certain new and useful Improvements in Furnaces, of which the following is a specification.

This invention relates to hot air furnaces, and an object of the invention is to provide 10 a hot air furnace, wherein a maximum radiating surface will be provided, to insure the proper heating of the air, during its passage through the furnace and prior to its delivery into the room to be heated.

Another object of the invention is to provide, in a hot air furnace, a sectional radiator structure, in connection with a chimney or stack draft arrangement which will direct the product of combustion from the 20 fire box of the furnace, through each section of the radiator prior to its exit from the furnace; also to provide a sectional radiator wherein the heating surface will be materially increased over the heating surface of 25 hot air furnaces commonly in use, resulting in a material saving of fuel, necessary to properly heat the air passing through the furnace.

A further object of the invention is to 30 provide a draft arrangement for the furnace which will direct the gases or products of combustion upwardly through the casing of the furnace in lieu of directing them toward the rear of the furnace.

Other objects of the invention will appear from the following detailed description, taken in connection with the accompanying drawings, forming a part of this specification, and in which drawings:

Figure 1 is a vertical section through the improved hot air furnace,

Fig. 2 is a vertical section through the furnace taken at right angles to the section illustrated in Fig. 1, and

Fig. 3 is a fragmentary vertical transverse section through the furnace.

Referring more particularly to the drawings, 1 indicates the casing of the hot air furnace which has a fresh air inlet pipe 2 50 communicating with the interior thereof near the bottom of the casing, and it has a plurality of hot or heated air outlet or exit pipes 3 connected thereto and communicating with its upper end, for conveying the 55 heated air to any desired location.

The casing 1 also has the usual form of

fire box 4 positioned centrally therein, access to which is gained through a door 5 in the casing. An ash pit 6 is formed within the casing 1 beneath the grate 7 of the fire box. 60 and a door 8 communicates with this ash pit to permit the shaking of the grate 7 and the removal of ashes from the pit.

As will be noted, by reference to Fig. 2 of the drawings, the fire box 4 and the ash 65 pit 6 take up only a portion of the interior of the lower part of the casing 1.

A sectional radiator structure is positioned above the fire box 4 and it includes a plurality of vertically extending plates 9, 70 certain of which have their upper and lower end connected by horizontal plates 10. These plates 9 and 10 provide a plurality of spaces, 11 and 12. The spaces 12 have communication with the interior of the fire box 75

4, for permitting the upward passage of the product of combustion from a fire in the fire box. These products of combustion pass from the spaces 12, through relatively small openings 13, into a horizontal pipe 14 which extends transversely through the casing 1 near the upper end thereof and does not have communication with the spaces or compartments 11. The pipe 14 projects beyond

the front side of the casing 1 and has a removable cap 15 mounted thereon, to permit of cleaning of the interior of the pipe. The end of the pipe opposite from the cap 15 projects outwardly through the rear side of 80 the casing 1 and has communication with

the stack 16 of the furnace structure. This stack 16 has communication, at its lower end, with a horizontal pipe 17. The horizontal pipe 17 enters the casing 1 and has communication with the rearmost compartment 12, as clearly shown in Fig. 1 of the 85 drawings. A damper, 18 of the butterfly type is positioned within the pipe 17 between its communication with its rearmost compartment 12 and the stack 16 for regulating the draft through the fire-box 4 and stack 16.

When the damper 18 is closed, all of the products of combustion from the fire-box 4 are forced to travel upwardly through the spaces 12, openings 13, into the pipe 14, through which they are drawn into the stack 16 for atmospherical distribution.

However, by adjustment of the damper 18, the quantity of the product of combustion passing upwardly through the spaces 12 110 may be regulated, and consequently the heating of the various plates 9 and 10 may

be regulated. These plates 9 and 10 form radiating surfaces for heating the fresh cool air which enters into the casing 1 through the pipe 2. This fresh cool air entering the casing 1 near the lower end of the same passes about the fire box 4, ash pit 6, and upwardly into and through the spaces 11. These spaces 11 are positioned alternately with respect to the spaces 12, so that the air, passing upwardly therethrough, will be subjected to the radiating heat from the plates 10 and 9, upon each side of the respective space through which the air is traveling, consequently resulting in the thorough heating of the fresh air, and permitting the maximum heating of the air upon the utilization of a minimum quantity of fuel, in the fire box. It is a well known fact that heated air will rise, and as the fresh air becomes heated, it will rise into the top of the casing 1 above the upper ends of the various compartments or spaces 11 and 12, and pass outwardly to the pipes 3 for distribution at the desired point or points. It is to be noted that the radiator construction extends outwardly on opposite sides of the fire box and the lower ends of the spaces which project beyond the fire box are open at their lower ends, so as to permit the fresh air entering the casing to flow through the said spaces 11.

The outer end of the pipe 17 is closed by a hinged closure 19 which permits access to the interior of the said pipe for cleaning it.

From the foregoing description, taken in connection with the accompanying drawings, it will be seen that a hot air furnace, embodying a maximum radiating surface, for heating the fresh air is provided, and that such a furnace will further permit the heating of the air to the desired thermal degree, with the use of a much less quantity of fuel than is necessary to heat the air to the same degree in hot air furnaces, commonly in use.

Changes in details may be made without departing from the spirit of this invention, but;

50 I claim:

1. In a hot air furnace, the combination, of a casing, a fire-box within said casing, a plurality of vertical and horizontal plates within said casing and dividing the space above said fire-box into a plurality of vertical compartments, the alternate of said compartments having communication with said

fire-box, a pipe extending horizontally through said casing near the upper end of said compartments, said pipe provided with 60 a plurality of openings each communicating with one of said alternate compartments, and a stack having communication with one end of said horizontal pipe.

2. In a hot air furnace, the combination, 65 of a casing, a fire-box within said casing, a plurality of vertical and horizontal plates within said casing and dividing the space above said fire-box into a plurality of vertical compartments, the alternate of said compartments having communication with said fire-box, a pipe extending horizontally through said casing near the upper end of said compartments, said pipe provided with 70 a plurality of openings each communicating with one of said alternate compartments, a stack having communication with one end of said horizontal pipe, a second horizontal pipe having communication with said alternate compartments near their 75 lower ends, and with said stacks, and a damper in said last mentioned horizontal pipes to regulate the communication between the stack and said compartments, near their lower ends. 80

3. In a hot air furnace, the combination, 85 of a casing, a fire-box within said casing, a plurality of vertical and horizontal plates within said casing and dividing the space above said fire-box into a plurality of vertical compartments, the alternate of said compartments having communication with said fire-box, a pipe extending horizontally through said casing near the upper end of said compartments, said pipe provided with 90 a plurality of openings each communicating with one of said alternate compartments, a stack having communication with one end of said horizontal pipe, a second horizontal pipe having communication with 95 said alternate compartments near their lower ends, and with said stacks, a damper in said last mentioned horizontal pipes to regulate communication between the stack and said compartments, near their lower ends, the spaces adjacent said alternate compartments having communication with 100 the interior of the casing exteriorly of the fire-box, a fresh air inlet at the lower end of said casing and outlet pipes having communication with the upper end of said casing for receiving air from said adjacent compartments. 105

WILLIAM H. NEHLS.
